UNITED STATES PATENT OFFICE

EDWARD C. DEARDEN, OF MERION, PENNSYLVANIA, ASSIGNOR, BY MESNE ASSIGNMENTS, TO SLOANE-BLAUBON CORPORATION, OF NEW YORK, N. Y., A CORPORATION OF DELAWARE

MANUFACTURE OF MOSAIC FABRICS

Application filed January 17, 1930. Serial No. 421,368.

My invention is designed to provide a laminated mosaic fabric suitable for floor coverings and the like, and having the design or pattern accentuated by inequalities in the surface level of the tesserae forming the mosaic, and particularly by the depression of tesserae or strips forming joint-like spaces between the more prominent tesserae or plaques embodied in the design.

10 My improvements are particularly designed to avoid difficulties and deterioration resulting from embossing an assembled linoleum product, or from subjecting the tesserae to unequal pressures with resulting variations in density, or from attempting to unite the edges of tesserae of dissimilar type and condition, such, for instance, as tesserae of cured and uncured linoleum.

15 By my improvements there is provided a flexible laminated mosaic fabric having a surface in relief, and composed of tesserae of substantially uniform density homogeneously united along the edges of abutting tesserae, all of which are composed of moulded granular linoleum composition of analogous texture and intermingled before curing, but having finished surfaces of different heights due to differences in the depth of material deposited for different tesserae, the deposits

20 of different depths being separately compacted before curing.

25 In accordance with my improvements, a flexible backing, such as burlap, felt, or the like, has deposited thereon uncured granular linoleum composition in the form of intersecting ribs or ridges or of spaced tesserae preferably providing a skeleton outline of a pattern. Such composition is compacted by means of a suitable press or rollers while

30 softened by heat.

The lattice or grid formed by the compacted ribs or bands of deposited linoleum has the spaces or interstices between the ribs or spaced tesserae filled with uncured granulated plastic linoleum composition to a depth greater than the depth of the original deposits, so that when such secondary deposits or insets are compacted by means of a press, while softened by heat, they are intimately united with the uncured previously

compacted primary deposits, but projected above the same. The lower surfaced tesserae definitely outline the contour of the pattern and produce light and shadow lines of pleasing effect, giving particularly a close simulation of tile, slate-stone, flagstone, brick or other paving plaques laid in mortar.

35 In the preferred practice of my invention, the backing is moved step by step beneath one or more stencils or templates having cut 55 therein slots or apertures for the passage of granular material, which, when deposited, outline a desired skeleton pattern. The number of templates or stencils used for the deposit of the material forming the lower portions of the surface will depend upon the 60 number of colors desired in the depressed portion of the product, and where a mortar joint effect is desired a single stencil will ordinarily suffice for the deposit of the composition therefor.

40 The plastic material to be attached to the backing, such as unseasoned granular linoleum composition, may be swept over the surface of the first stencil, and the portion thereof of passing through the stencil openings forms outline ribs or spaced tesserae on the 65 backing to a depth equal to the space between the top of the backing and the stencil. If more than one stencil is used for the deposit 70 of ribs or spaced tesserae, the burlap is moved step by step beneath the stencils in sequence and receives deposits from each stencil. The 75 material so deposited is softened by heat and attached to the backing by pressure, resulting in the production of a backing having thereon a projecting reticulated pattern of uncured composition with openings or recesses therein.

45 After the compacting of the initial deposit, 90 the backing is moved step by step beneath one or more additional templates having apertures for the passage of material to fill the 95 openings or recesses in the pattern to a greater depth than the original deposit. The number of templates or stencils used for the deposit of material forming insets will depend upon the number of colors desired in the insets, a separate stencil being usually used for each color desired. The composition 100

used to form the inserts is preferably swept over the appropriate stencil, and the portion of the composition passing through the stencil openings forms deposits having a depth equal to the space between the backing and the stencil. The deposited granular material forming the insets is softened by heat and compacted by pressure and firmly united to both the backing and previous deposits, 10 which is again softened by the second heating, but is not again directly subjected to pressure. The templates or stencils containing passages for the deposit of material to form tesserae having surfaces below the general 15 surface level of the finished product are preferably positioned closer to the backing than are the stencils or templates containing passages for the deposit of material to form tesserae which are to form the higher portions 20 of the surface of the completed product, and each set of stencils may be elevated by suitable means during the movement of the backing.

The pressures applied to the initial and 25 secondary deposits are preferably such as to secure a substantially uniform density in both groups of tesserae, and the heat softened initial and secondary deposits are firmly united to one another by the intermingling of granules along their abutting edges and the partial overlying of the initial deposit by the secondary deposit.

The backing with its compacted covering is 30 then finished by curing and seasoning, preferably after being subjected to the action of a suitable finishing press conforming to the surface of the product.

The preferred practice of my invention and the product resulting therefrom are diagrammatically illustrated in the accompanying drawing, in which Fig. 1 is a fragmentary plan view illustrating a backing and a template for depositing thereon an initial grid-like set of tesserae, the template being broken away to show the backing and the material deposited in granular condition; Fig. 2 is a transverse sectional view on the line 2—2 of Fig. 1; Fig. 3 is a transverse sectional view illustrating the compacting of the initial deposit by a press; Fig. 4 is a fragmentary plan view of a backing on which a reticulated deposit has been compacted and a template for depositing insets between the initial deposits, a portion of the template being broken away to show the patterned backing with the insets deposited thereon in granular condition; Fig. 5 is a transverse sectional view on the line 5—5 of Fig. 4; and Fig. 6 is a transverse sectional view of a fabric and press for compacting the insets.

As graphically illustrated in the drawing, the backing 1, preferably consisting of burlap, impregnated felt or the like, is moved step by step beneath one or more templates or stencils 2 containing apertures 3 having

the contour of tesserae comprised in the design to be produced. As illustrated, the passages may have a gridlike outline, so that tesserae formed from uncured plastic granular linoleum composition deposited there-through will simulate mortar joints. Any desired number of stencils may be utilized for the deposition of the tesserae to simulate mortar joints, and variously colored plastic compositions may be used with the respective templates. The material passing through the apertures 3 is deposited on the backing in the form of intersecting ribs or ridges 4 having between them the recesses or openings 5.

The further movement of the burlap carries the deposited granular material beneath the head 6 of a conventional form of steam heated hydraulic press, and the material comprised in the ridges 4 is compacted thereby to approximately one-third its initial thickness, so that the granules are united into an integral fretwork or grid firmly adhering to the backing.

Further step by step movement of the backing brings the recesses between the ribs into registration with apertures 7 of one or more templates or stencils 8. The template 8 is positioned at a greater distance from the backing than the stencil 2, and the apertures therein have contours conforming to the outline of the inset tesserae to be formed in the recesses or openings 5. Granulated, uncured, plastic linoleum composition is brushed through the opening 7 and forms deposits in the openings 5 of greater depth than the original depth of the ridges 4. Further step by step movement of the backing carries it beneath the head 9 of a second steam heated press which acts upon the loose granular material 10 in the openings or recesses 5 and compacts such material to approximately one-third its initial thickness. The heat and pressure not only unite the granules of the deposits 10 with one another, but also with the softened, uncured compacted material of the ridges 4 and to the backing.

The laminated product may, if desired, be subjected to the further action of a finishing press and then cured and seasoned with the production of a covering having a homogeneous surface lamina of irregular height simulating paving plaques spaced by mortar joints, or, by suitably shaping the template apertures, the pattern deposited may be so shaped and colored as to produce flowers, birds, geometrical figures, or any other desired appearance.

While I prefer that the plastic compositions involved in my invention be composed of oxidized linseed oil, granulated cork, wood flour, gums and pigments, other binders and fillers may be used in the composition, such for instance, as ground leather, asbestos, and plastic cellulose. All such solidifiable compositions are intended to be embraced within the term

linoleum composition as used in the claims, whether or not such composition actually contains any linseed oil.

Having described my invention, I claim:—

1. The method of making moulded inlaid linoleum which consists in depositing on a backing unseasoned granulated plastic linoleum composition forming tesserae having spaces between them, compacting such deposited composition, depositing between compacted tesserae aforesaid unseasoned granulated plastic linoleum composition, and compacting said last named deposited composition.
- 15 2. The method of making moulded inlaid linoleum which consists in depositing on a backing a granulated plastic in the form of tesserae having spaces between them, compacting such deposits, depositing between such compacted deposits granulated plastic material to a greater depth than the initial deposits, and compacting such secondary deposits so as to form a surface above the surface of said initial deposits.
- 25 3. The method of making moulded inlaid linoleum which consists in moving a backing beneath an apertured stencil, passing plastic uncured granulated linoleum composition through said stencil apertures to form spaced deposits on said backing, softening and compacting said deposits, moving said backing into registration with apertures of a stencil conforming with spaces between said compacted deposits, passing plastic uncured granulated linoleum composition through said last named apertures to form deposits of greater depth than said first deposits, softening said first and second deposits and compacting said second deposit.
- 35 4. The method of making moulded inlaid linoleum which consists in moving a backing beneath stencils outlining different shapes in sequence, depositing linoleum composition on said backing in shapes outlined by said stencils, deposits aforesaid being made from different distances from said backing, compacting the initial deposit on said backing before the second deposit is made thereon, and compacting the second deposit without direct pressure on said first deposit.

In witness whereof I have hereunto set my name this 31st day of December, 1929.

EDWARD C. DEARDEN.
